United States Patent Office

Des. 181,744
Patented Dec. 17, 1957

181,744

TOY DOG

Anna Edwarda Moszczynski, New York, N. Y.

Application January 18, 1956, Serial No. 39,839

Term of patent 14 years

(Cl. D34—2)

Fig. 1.

Fig. 2.

Fig. 3.

Fig. 1 is a front view of a toy dog embodying my design;

Fig. 2 is a side view thereof; and

Fig. 3 is a rear perspective view.

The characteristic features of the design reside in those features shown in solid lines.

I claim:

The ornamental design for a toy dog, as shown and described.
